[57] CLAIM

The ornamental design for a punch, as shown and described.

DESCRIPTION

FIG. 1 is a top perspective view of a punch with the lid member in a closed position, showing my new design; FIG. 2 is a front perspective view with the lid member in an opened position;

FIG. 3 is a rear elevational view of FIG. 2;

FIG. 4 is a top plan view of FIG. 1;

FIG. 5 is a rear elevational view of FIG. 1;

FIG. 6 is a side elevational view of FIG. 1, the opposite side being a mirror image thereof;

FIG. 7 is a front elevational view of FIG. 1;

FIG. 8 is a bottom plan view of FIG. 1; and

FIG. 9 is a cross-sectional view taken in the direction of arrows 9—9 in FIG. 3.
